(57) CLAIM

The ornamental design for a food serving plate with diamond pattern rim, as shown and described.

DESCRIPTION

FIG. 1 is a perspective view of a food serving plate with diamond pattern rim showing my new design;

FIG. 2 is a top plan view thereof;

FIG. 3 is a side elevational view thereof, all sides being the same;

FIG. 4 is a bottom plan view thereof; and,

FIG. 5 is a bottom plan view of a food serving plate with diamond pattern rim showing a second embodiment of my new design, all other sides the same as the first embodiment.
